United States Patent Office.

GARDNER HERRICK, OF ALBION, MICHIGAN.

Letters Patent No. 92,445, dated July 13, 1869.

SAD-IRON HEATER.

The Schedule referred to in these Letters Patent and making part of the same.

To all whom it may concern:

Be it known that I, GARDNER HERRICK, of the village of Albion, in the county of Calhoun, and State of Michigan, have invented a new and useful Improvement in Sad-Iron Heaters; and I do hereby declare that the following is a full, clear, and exact description of the construction and mode of operation of the same, reference being had to the annexed drawings, in which—

Figures 1 and 2 represent, in perspective, exterior and interior views of the heater.

Similar letters of reference indicate like parts in both the figures.

My invention relates to an arrangement of parts in a portable heater, by which the flame from the combustion of petroleum or other hydrocarbon-oils, or from any of their gaseous or refined liquid products, may be employed to heat sad-irons more conveniently, economically, and effectively than heretofore; and the better to enable others skilled in calorifics to construct my said heater, I will now proceed to describe it.

For general domestic use, I usually construct my improved heater hexagonal, for heating but six irons, but it may be a polygon of more or less sides, as desired.

A represents the bottom, or base, being simply a basin, with polygonal flaring sides, and usually mounted on legs, one of which is seen at a.

The upper edge of this basin is furnished with a narrow projecting ledge, on which to rest the irons to be heated, as seen at e, and also with a groove, f, to receive the lower edge of the conforming-sided pyramidal radiator, to be hereinafter more fully described.

The bottom of the basin A has a central opening, o, through which the fuel-supply pipe P passes, to any suitable burner B, furnished with flame-jet apertures or tubes around the sides, as at j, so that the said flame-jets from these lateral issues, aided, when necessary, by air-currents from the bottom apertures b, may act with the most advantageous effect in heating the sides of the pyramidal radiator C aforesaid.

To further concentrate and direct the flame-heat, I place inside of the radiator what I term a deflector, as seen at D, in fig. 2, where the radiator is supposed to be removed, for the purpose of exhibiting the interior.

The deflector is a counterpart of the radiator, as to the number and inclination of its sides, but is of less diameter, and is provided with a bottom, which, together with a portion of the side, is not shown in the drawing, for the purpose of exposing to view the arrangement of the burners and supply-pipe underneath.

The deflector is steadied in place, and supported at the proper height, on legs (only one of which is shown,

at d,) which rest on the bottom of the basin A, in the interior angles of the polygonal sides.

When the deflector and radiator are placed in their respective positions, as described, a narrow open flue-space is formed between them, to receive from the burners the side flame, in such manner as to act directly upon and heat the inclined polygonal side plates of the radiator, and through them the sad-irons placed outside, one of which is seen at F.

To protect the handles of the sad-iron and the radiation of heat into the room, I employ what I term a slotted shield cover, E, over the radiator C.

This shield conforms, in number and inclination of its sides, with the radiator, but is enough larger in radius to leave an intervening space all around for the reception of the irons, and a slot, S, open at bottom, is made, as seen, in the centre of each side, in which the handles are slid when placing or removing the irons on and from the radiator.

The outer cover just mentioned forms a hollow pyramidal frustum of six sides, cast in one piece, in the flat apex of which a wire bail, m, or other handle, for carrying the heater, is attached; also perforations for ventilation, and a griddle-hole, G, fitted with a cover, are usually made in it, for convenience in heating water, &c., during the operation of ironing or at other times, in warm weather, or in case of sickness or other requirements at night.

It may be desirable to break the continuity of space under and around the shield, for some special reason. This can be readily done by corrugating the angles.

Two bent rods, (heads seen at n,) passing down through the heating-space, and nutted under the bottom, secure the several parts of the heater together.

A reservoir to contain the liquid fuel to be burned is connected to the pipe, and, when required, a cock to graduate the supply.

A lamp-burner in connection, to furnish light, will be found convenient, also; but I did not deem it necessary to exhibit these adjuncts, as their general form and arrangement are familiar to all.

Any of the inflammable carbon or hydrocarbon-oils, either in a crude or refined liquid, or gaseous state, that are safe and suitable for heating-purposes, may be used as fuel in my heater, provided the flames from the burners are in such contiguity with the side-plates of the radiator, and impinge in such direction, as will best impart their heat, substantially as seen by the red arrows.

The system of air-supply in the heater, and the necessity for the use of a chimney in the apex of the shield, will depend, of course, upon the nature of the fuel and the arrangements in burning it, and the style of burner must of necessity correspond.

I do not claim pyramidal radiators, with housings on the sides to admit the sad-irons, as new in themselves, as these are embraced in a coal-burning heater patented by J. H. Yates, August 20, 1867; but

What I do claim as my invention, and desire to secure by Letters Patent, is as follows:

I claim the arrangement and combination of the base A, deflector D, radiator C, and slotted shield-cover E, with each other, and with a suitable central

burner B, when said burner is fed from a reservoir connected therewith, and its flame directed and applied substantially in the manner and for the uses set forth.

GARDNER HERRICK.
